UNITED STATES PATENT OFFICE

141,016

DESIGN FOR AN END CABINET

Jacques Stanitz, Warren, Ohio, assignor to
Mullins Manufacturing Corporation, Salem,
Ohio, a corporation of New York

Application December 1, 1944, Serial No. 116,641

Term of patent 7 years

(Cl. D33—19)

To all whom it may concern:

Be it known that I, Jacques Stanitz, a citizen of the United States, residing at Warren, in the county of Trumbull and State of Ohio, have invented a new, original, and ornamental Design for an End Cabinet, of which the following is a specification, reference being had to the accompanying drawing forming part thereof.

The single figure in the drawing is a perspective view of an end cabinet showing my new design.

The opposite side of the cabinet is plain and the recessed base portion is the same as shown in the drawing figure. The other end of the cabinet is a plain flat surface. The characteristic features of my design are shown by means of full lines in the drawing.

I claim:

The ornamental design for an end cabinet, substantially as shown and described.

JACQUES STANITZ.
